UNITED STATES PATENT OFFICE.

FRANK P. JOHNSON, OF WALTHAM, MASSACHUSETTS.

DUMPING-CAR.

SPECIFICATION forming part of Letters Patent No. 254,138, dated February 28, 1882.

Application filed December 27, 1881. (No model.)

To all whom it may concern:

Be it known that I, FRANK P. JOHNSON, of Waltham, in the county of Middlesex and State of Massachusetts, have invented a new and useful Improvement in Devices for Dumping Railroad-Cars or other Similar Vehicles for the Transportation of Gravel, Coal, &c., which invention I will describe as follows, reference being had to the accompanying drawings, which form a part of this specification, like letters indicating like parts in the different figures thereof.

Figure 1 of the drawings shows in perspective an ordinary gravel-car with my device seen as applied in the manner that I consider the best when the car is provided with iron corner-posts. This figure shows my device upon three corners of the car, though all four of the corners are equipped alike in practice. Fig. 2 illustrates the appliance in perspective, as seen in Fig. 1, but detached from the car, so that all its parts may be shown fully and in detail. Fig. 3 is a view in perspective, showing the device detached from the car, and illustrating the best manner, in my opinion, of attaching my appliance to wooden corner-posts. Fig. 4 is a view in perspective of the adjustable detachable lifting or dumping lever, the application and operation of which is illustrated in Fig. 1.

My invention consists in what may be termed a "fixed segment-gear" attached to each of the four corner-posts of a gravel-car or other similar vehicle, or preferably, for strength, should be cast with the corner-post when said post is of iron, the segment-gear being preferably of iron, as the following description will render obvious; but when the corner-posts are of wood said gear should preferably be inserted in the post, so that the face of the body of the gear shall be flush with the face of the corner-post, and the gear bolted or otherwise attached to said post in any suitable manner, the post to be mortised for the admission of the gear; but the gear may be attached to without being inserted in the corner-post. A pin is inserted in said segment-gear by means of an ordinary thread, as shown in the drawings, the inner end of said pin being upset in order to hold it in place; or the pin may be inserted and held

in place by any suitable and well-known means. Said pin is provided with an annular lip or flange to prevent the lifting-lever from slipping off thereof. The lifting-lever is so shaped that it can be passed over said flanged pin and then readily held thereon, the form of construction of said lever also admitting of placing the same between and bearing it against the cogs of the segment-gear, said lever being readily placed in said gear at any angle rendered necessary by the height of the operator, the position of the body of the car, or by the relative configuration of the ground upon which the operator is to stand.

Owing to the necessity of removing the extended ends of the side sills of the car in order to secure the free movement of the lever required, I supply the strength taken from said side sills by the removal of said ends by adopting means in themselves not novel, but new in combination with this device, which means will be hereinafter fully set forth.

The following is a full, clear, and exact description of the construction of my device, of its application to a dump-car, and of its operation.

Each of the four corners E of the car A is provided with the fixed segment-gear B, and arranged upon and forming a part of said segment-gear are the cogs b, as shown. As the more common mode of construction at present is to make the corner-posts of gravel-cars of iron, Figs. 1 and 2 of the drawings show my invention applied to iron corner-posts; and though the segment-gear may be bolted or otherwise attached to said iron corner-post, I believe it to be better to cast both the segment-gear B and the post E together to secure greater strength.

An examination of an ordinary gravel-car shows that the two side sills, H, are carried a little beyond the corner of the car, and that in the case of iron corner-posts said posts are usually cast so as to extend out upon and to the end of said extension of said sill, for the purpose of strengthening the corner of the car. As is obvious, said extensions at each end of each of the two side sills, H, must be cut off in order to give proper and sufficient room for the operation of the lever D; and in order to

make good the loss of strength occasioned by the removal of the ends of said sills H, I carry the iron plate J farther along in the sill H than is usual, the use of said plate J being customary; but it is not usually carried as far into the sill H as is shown in Figs. 1 and 2. The plate J is so placed in the sill as that the surfaces of the sill and of the plates shall be flush with each other, and then held in its place in 10 the sill by the bolts for their equivalents. The piece of iron J' is also carried into the sill, as shown in Figs. 1 and 2, for the purpose of lending increased strength; but for those pieces or plates J and J' I claim no novelty in themselves, but only in combination with this particular construction of my device—that is to say, when the invention is applied to iron corner-posts. When said corner-posts are of iron I believe the better mode of construction to 20 be by casting said post E, the segment-gear B, the cogs b, and the two plates J and J' all together, as shown in Figs. 1 and 2, for though the segment-gear B may of course be bolted or in some other of the well-known ways attached to the corner-post, it is obvious that the mode of casting all in one piece gives greater strength. The pin G is provided with the lip or flange g', to prevent the lever from slipping off therefrom, and is inserted in the segment- 25 gear B, either by means of the thread g, as shown in Figs. 2 and 3, and upset at its inner end for the purpose of holding it in place, or it may be inserted in any suitable manner.

The cogs b may of course be attached to the body of the segment-gear B; but in order to insure requisite strength they should be cast as a part of said gear, as before stated.

Fig. 4 shows the adjustable detachable lever, the entire lever taken together being designated D. In Fig. 1 is seen said lever adjusted upon the pin G, and in the hands of the operator, ready for work. The part C of the lever D should be of iron, and preferably carried over and attached to the handle C' by means 45 of the bolts d, but may be attached thereto in any other equivalent and suitable manner.

The handle C' may be of wood, or of any suitable material, or the two parts C and C' may be made in one piece, of iron or any sufficiently strong material. The part C is larger at the end next to the handle C', so that it may be passed over the lip g' of the pin G in adjusting, after which the lever is drawn so as to bring the small end thereof to a bearing upon 55 the periphery of the pin G, as illustrated in

Fig. 1. The lever is so made that the double arms d' will fit between and bear against the cogs b, as illustrated in Fig. 1. The inside surfaces of the double arms d' ought preferably to be made convex at the smaller end of 60 said double part, so that the lever may work readily and freely upon the pin G.

Fig. 3 shows my device as applied to a wooden corner-post, and attached thereto preferably by the bolts b'; but it may be attached 65 in any other suitable manner. The sills H must be cut off at their ends for the same reason as before stated, and the usual way of building wooden-posted cars being to insert the corner-post E in the sill H, as shown in 70 Fig. 3, I, in order to make good the loss of strength occasioned by the removal of the ends of said sills, (which ends are ordinarily connected with wooden corner-posts by an iron rod or brace for strength,) attach the piece of 75 angle-iron h to the sill and to the post by means of the bolts h' or equivalent means, or by the use of any equivalent of the angle-iron, to insure the requisite strength to the corner of the car; but I make no claim to said 80 angle-iron as used in itself, but only in combination with this construction and application of my device.

In view of the very clear illustration of the operation of this device furnished by Fig. 1 of 85 the drawings, it seems hardly necessary to enter into any extensive description of its practical working. I calculate that one man with a lever, D, at each of two opposite or diagonal corners of a car can readily dump a modern- 90 built loaded dump-car, while three or four times this number of men is required to dump a loaded car by a direct lift.

Having fully described my invention and the manner of carrying the same into effect, what 95 I claim as new, and desire to secure by Letters Patent, is—

In a dumping device, the segment-gear B, with cogs b, the corner-post E, with elongated strengthening-plate J, and strengthening-plate J' inserted in and attached to the sill H, the pin G, with lip g', and the adjustable detachable lever D, constructed and arranged substantially as described and shown, and for the purpose set forth.

FRANK P. JOHNSON.
